(57) **CLAIM**

The ornamental design for a pediatric crown, as shown and described.

DESCRIPTION

FIG. 1 is a perspective view showing a first embodiment of a new design for a pediatric crown.

FIG. 2 is a top view thereof;

FIG. 3 is a right-side view thereof;

FIG. 4 is a front side view thereof;

FIG. 5 is a bottom view thereof;

FIG. 6 is a cross-sectional view taken along line 6-6 of FIG. 5; and,

FIG. 7 is a cross-sectional view taken along line 7-7 of FIG. 5.

The portions of the pediatric crown in FIGS. 1-7 shown in broken lines are included to show features that form no part of the claimed design.
